VACUUM CLEANER

George W. Allen, Boston, Mass., assignor to
B. F. Sturtevant Company, Boston, Mass.

Application October 11, 1938, Serial No. 234,391

1 Claim. (Cl. 15—16)

This invention relates to vacuum cleaners and relates more particularly to vacuum cleaners of the manually propelled type.

Vacuum cleaners of the ordinary manually propelled type, for example, are usually provided with levers which may be adjusted by a hand or foot of the operator to raise or lower the cleaner nozzle as floor coverings of varying depth and porosity are encountered. For example, a vacuum nozzle moving over a relatively porous rug should be relatively close to the rug. If the same nozzle without adjustment were moved over a less porous rug, the resistance to air flow would be too great, tending to overload the cleaner, to produce too great a suction and to cause the rug to adhere to the nozzle. In the past, in order to permit vacuum cleaners to operate most efficiently, it has been necessary for the operator to adjust levers to lower the cleaner nozzle as relatively porous rugs were encountered and to raise the nozzle when less porous rugs were encountered. Such adjustments have depended upon the operator's judgment with the result that in many cases nozzles set too high have been ineffectively used for cleaning relatively porous rugs, or nozzles set too low have been used for cleaning relatively non-porous rugs to overload the cleaner and to add to the difficulty of moving same.

This invention provides a vacuum nozzle which is automatically raised and lowered in response to changes in vacuum caused by varying resistances in the material being cleaned, to maintain a desired predetermined suction at the material being cleaned and to maintain accordingly, the cleaner in the most efficient operating condition. As relatively porous floor coverings are encountered, the nozzle lowers itself to maintain the desired suction. Then as less porous floor coverings are encountered, the nozzle raises itself to maintain the desired suction.

An object of the invention is automatically to maintain the nozzle of a vacuum cleaner at the proper distance from the surface being cleaned so as to provide the proper suction, as it is moved over materials having various degrees of porosity.

Another object of the invention is automatically to raise and lower the nozzle of a vacuum cleaner in response to changes in suction therein as it is moved over materials having various degrees of porosity.

Other objects of the invention will be apparent from the following description and from the drawing.

The invention will now be described with reference to the drawing, of which:

Fig. 1 is a profile view with a portion broken away, of a vacuum cleaner embodying this invention;

Fig. 2 is a plan view of the bottom of the cleaner of Fig. 1, and

Fig. 3 is a sectional view along the lines 3—3 of Fig. 2.

The embodiment of the invention illustrated 10 includes the stream-lined casing 5 which terminates at its front end in the nozzle cover 6 and at its rear end in the connection 7 to the dust receiving bag 8. The usual electric motor 9 drives the usual blower wheel 10 for providing the 15 necessary suction.

The cleaner nozzle 11 includes the converging walls 12 between which the air into the cleaner enters. The nozzle 11 has a rear extension 13 forming the lower portion of the inlet passage to 20 the wheel 10. The extension 13 has the rear hinge portion 14 which is hinged at 15 to the cleaner frame.

The nozzle 11 and its rear extension 13 is connected to the nozzle cover 6 and to the lower 25 housing of the wheel 10 by the flexible material 26 which, for example, may be rubber and the purpose of which, is freely to permit up and down movement of the nozzle 11 about its hinge 15, while at the same time it forms such an effective air seal that no air can enter the cleaner except at the nozzle lips 19 formed by the lower portions of the nozzle walls 12.

The rotary sweeper brush cylinder 16 is attached by the screws 17 to the end walls 18 of the 35 nozzle and is adapted to be rotated during operation of the cleaner, by the belt 19 driven by the motor 9.

The converging walls 12 of the nozzle 11 and to some extent the rear extension 13 of the nozzle, 40 act during the operation of the cleaner as a suction responsive diaphragm movable through the suction exerted by the blower wheel 10. As the resistance to air flow through the nozzle increases due to its movement over a thicker or 45 more closely woven floor covering, the suction in the nozzle increases and this increase in suction acting upon the lower walls of the nozzle, lifts the nozzle upwardly to provide a greater spacing between the nozzle lips and the material 50 being cleaned, to reduce the air resistance and the suction to normal. When the nozzle passes from a closely woven floor covering onto one more porous or onto a bare floor, the weight of the nozzle becomes greater than the suction force 55

acting upwardly upon its walls and the nozzle is automatically lowered to restrict the air inlet area and to conformably increase the air resistance and the suction to normal.

- 5   6 The brush cylinder 16 in the embodiment illustrated is lifted and lowered with the nozzle and this is preferred. The nozzle could of course move independently of the brush cylinder when brush cylinders are used, or could be used without 10 out a sweeper cylinder.

In the annexed claims the term "vacuum cleaner" refers to what are also known as vacuum sweepers.

While one embodiment of the invention has 15 been described for the purpose of illustration, it should be understood that the invention is not limited to the exact apparatus and arrangement of apparatus illustrated and described since many departures therefrom may be suggested by those 20 skilled in the art without departing from the invention.

What is claimed is:

In a vacuum cleaner having a blower wheel, a lower housing having substantially horizontal

flanged walls extending below said wheel, a suction nozzle including a rearwardly extending plate having a central portion having a large area extending underneath said wheel and having upper flanged walls parallel to said walls of said housing, a nozzle cover having flanged lower walls extending substantially parallel to and normally spaced from the upper walls of said nozzle, a flexible diaphragm extending completely around said nozzle and extending between and 10 attached to said flanged walls, the walls of said nozzle, said cover, said housing and said diaphragm forming an air passage connecting with said wheel, said diaphragm permitting said nozzle to be moved towards said cover in response to 15 suction on said nozzle walls, said housing having a large lower opening between said first mentioned flanged walls, extending above said plate whereby said plate provides a relatively large area for positive actuation under a small pressure 20 differential, and means pivoting the rear portion of said plate to said housing.

GEORGE W. ALLEN.
